UNITED STATES PATENT OFFICE

2,506,808

FRAME-SUPPORTED HOPPER

Leonard B. Neighbour, Moline, and Henry E. Korum, East Moline, Ill., assignors to Deere & Company, Moline, Ill., a corporation of Illinois

Application November 30, 1945, Serial No. 632,075

2 Claims. (Cl. 220—1)

1

The present invention relates generally to tubular frame construction, and more particularly to frame construction of the type applied to hoppers, bins, enclosures, and the like, and has for its principal object the provision of a novel and improved frame construction which is simpler in design, lighter in weight, and easier to assemble and disassemble than frame construction heretofore known to those skilled in the art.

Another object relates to the provision of a light sheet metal hopper having a light but sturdy tubular frame and an inwardly and downwardly tapering sheet metal body, the hopper being supported on removable legs permitting a number of the hoppers to be nested together for shipping purposes, with the supporting legs removed. It is to be understood, however, that the type of construction disclosed herein is not to be limited to hoppers of this type, but we have found that construction of the type disclosed herein is well adapted to grain hoppers for receiving grain from a wagon or truck and delivering it to a blower type grain elevator.

These and other objects and advantages of our invention will be apparent to those skilled in the art after a consideration of the following description, in which reference is had to the drawings appended hereto, in which

Figure 1 is a top plan view of a hopper embodying the principles of our invention;

Figure 2 is an end elevational view of the hopper;

Figure 3 is a perspective view of one corner of the tubular frame structure, showing the details of the means for interconnecting the tubular members;

Figure 4 is an elevational view of one of the elbow castings for interconnecting the tubular members;

Figure 5 is a bottom plan view of the elbow casting shown in Figure 4;

Figure 6 is an elevational view of another elbow casting used in the construction of the hopper; and

Figure 7 is a bottom plan view of the casting shown in Figure 6.

Referring now to the drawings, the hopper is indicated in its entirety by reference numeral 10 and comprises a generally rectangular peripherally extending tubular frame 11 carried on a plurality of generally vertical tubular front and rear legs 12, and a sheet metal body or hopper bottom 13 depending from the peripheral frame 11.

The frame 11 comprises a pair of front and rear generally parallel straight tubular members 15,

2

16 and a pair of fore and aft extending, laterally spaced, straight tubular side members 17, 18. The adjacent ends of each pair of adjacent tubular members are interconnected by a right hand or left hand elbow casting member 20 or 21. Each of the elbows 20, 21 is in the form of a generally cylindrical casting member substantially equal in outer diameter to said tubular members and curved substantially in a right angle bend, each end of which is provided with a stub 22 of reduced diameter. Each of the stubs 22 is adapted to be inserted into the adjacent end of one of the tubular frame members and fits closely therein, and is provided with a diametrically extending aperture 23, which is adapted to register with diametrically aligned apertures 24 in the tubular frame member associated therewith, to receive a securing bolt 25 provided with a nut 26.

Each of the elbow castings 20, 21 is also provided with a depending stub 27, formed integrally therewith, and having a diametrically extending aperture 28. The depending stub 27 is adapted to be inserted into the upper end of one of the tubular legs 12, which is provided with diametrically aligned apertures near the upper end thereof for receiving a securing bolt 30 to secure the tubular leg 12 to the elbow casting.

It will be noted that the position of the depending stub 27 on the elbow casting is different in the two types of right and left hand castings 20, 21, in order to offset the tubular legs inwardly from the side edges of the peripheral frame 11.

The sheet metal hopper bottom 13 tapers downwardly and inwardly and rearwardly to direct the grain deposited therein toward a gate 32, centrally disposed in the back wall of the hopper, but the details of the gate are not an essential part of the present invention and therefore are not described herein. The upper edges of the sheet metal body 13 are curved over the top of the frame 11 as indicated in Figure 2 by reference numeral 33, and are secured to the tubular frame members 15, 16, 17, 18 by means of bolts 34, which are inserted through vertically disposed apertures in the tubular frame members, and suitable registering apertures in the sheet metal. Inasmuch as the elbow castings 20, 21 are substantially flush with the frame members 15, 16, 17, 18, the upper edges of the body lie smoothly over the peripheral frame. The rear legs 12 are secured to the back wall by means of lower bolts 35, indicated in Figure 2, beneath the securing bolt 30.

We claim:

1. A frame-supported hopper for the handling of bulk material such as corn, grain or the like, comprising: a plurality of straight members ar-

ranged generally in the form of a rectangle, each member being of substantially uniform cross-sectional area and shape throughout its length and each having opposite, socketed end portions of circular cross-section externally; a plurality of corner elements, each in the form of a combined elbow and T wherein each elbow is of circular cross-section that has a diameter substantially equal to the outside diameter of a socketed end portion of a straight member and each end of each elbow is reduced to fit and be received by the socketed end portion of an associated member, so that said members and elements when assembled provide a generally rectangular frame having rounded corners and adapted to be disposed generally horizontally with the T's projecting downwardly; a plurality of vertical legs, each having a socketed upper end portion within which a T fits and is received so that said legs sustain the frame; means including a plurality of imperforate walls joined together to provide a hopper depending below the general level of the frame, said walls having top edges delineating an open top for the hopper substantially coincident in size and shape with the frame and having rounded corners respectively concentric with the frame elbows, said top edges of the walls including flanged portions lying respectively along the straight members and elbows in a substantially continuous rectangular joint that is substantially impervious to leakage of material of the type aforesaid; and means securing the hopper to the frame and maintaining said joint.

2. A frame-supported hopper for the handling of bulk material such as corn, grain or the like, comprising: a plurality of elongated frame members arranged generally in the form of an open frame, each member being of substantially uniform cross-sectional area and shape throughout its length and each having opposite, socketed end portions; a plurality of connecting elements, each

in the form of a T having a crossbar and leg wherein each crossbar is of a cross-sectional shape and area substantially the same as that of a frame member and each end of each crossbar is reduced to fit and be received by the socketed end portion of an associated member, so that said members and elements when assembled provide a generally open frame in which the joints between the frame members and connecting elements are relatively smooth, said frame being adapted to be disposed generally horizontally with the legs of the T's projecting downwardly; a plurality of vertical supporting legs, each having a socketed upper end portion within which a T leg fits and is received so that said supporting legs sustain the frame; means including imperforate wall structure providing a hopper depending below the general level of the frame, said wall structure having a top edge delineating an open top for the hopper substantially coincident in size and shape with the frame, said top edge of the wall structure including flanged portions lying respectively along the frame members and cross-bars of the connecting elements in a substantially continuous joint that is substantially impervious to leakage of material of the type aforesaid; and means securing the hopper to the frame and maintaining said joint.
